UNITED STATES PATENT OFFICE.

JAMES C. GRIFFIN, OF ERIE, PENNSYLVANIA, ASSIGNOR TO GRIFFIN MANUFACTURING COMPANY, OF ERIE, PENNSYLVANIA, A CORPORATION OF PENNSYLVANIA.

DESIGN FOR A HINGE-LEAF.

46,496.

Specification for Design.

Patented Oct. 6, 1914.

Application filed April 28, 1913. Serial No. 764,287. Term of patent 14 years.

To all whom it may concern:

Be it known that I, JAMES C. GRIFFIN, a citizen of the United States, residing at Erie, in the county of Erie and State of Pennsylvania, have invented a new, original, and ornamental Design for a Hinge-Leaf, of which the following is a specification, reference being had to the accompanying drawing, forming part thereof.

The figure is an elevation of a hinge leaf showing my new design, parts completing a hinge being shown in dotted lines to show the relation of parts with which my design may be used.

It will be noted that the leaf is raised, the raised portion presenting an unbroken surface and starting slightly in from the edge of the leaf forming a border around the raised portion.

I claim:

The ornamental design for a hinge leaf as shown.

JAMES C. GRIFFIN.
